UNITED STATES PATENT OFFICE.

CHRISTOPH RIESSNER, OF NEW YORK, N. Y., ASSIGNOR TO C. RIESSNER & CO., OF SAME PLACE.

CAN-JACKET.

SPECIFICATION forming part of Letters Patent No. 249,674, dated November 15, 1881.

Application filed October 4, 1881. (No model.)

To all whom it may concern:

Be it known that I, CHRISTOPH RIESSNER, of New York, in the county and State of New York, have invented certain new and useful 5 Improvements in Can-Jackets; and I do hereby declare that the following is a full, clear, and exact description thereof, reference being had to the accompanying drawings, and to the letters of reference marked thereon, which form 10 part of this specification, in which—

Figure 1 is a central vertical section of my jacket, and Figs. 2 and 3 are details of the same.

The nature of my invention consists in such 15 peculiarities of construction as will be herein-after more fully set forth.

In order that others skilled in the art to which my invention appertains may avail themselves of its benefits, I will now proceed to 20 describe its construction.

A indicates a cylindrical casing or jacket, made of any desired size and from any suitable sheet metal. In the sides of this jacket are open spaces, divided by bridges *a a*, upon 25 which may be stamped the quantity of milk or other fluid in the inclosed can when the top of said fluid is on a level with any one of the bridges. The jacket is also preferably corrugated in order to strengthen or stiffen it.

30 C represents a sheet-metal ring, which is inserted at the bottom of the cylinder A. The upper edge of this ring is turned inward, as seen at *b*, to form a ledge, upon which rests the can. Its lower edge is turned outward and upward around the lower edge of the jacket, and

may then be wired in the usual manner. After the ring C is properly inserted, as described, a pointed punch is driven at intervals through both jacket and ring from their outer sides, leaving a ragged edge around the hole thus 40 formed, and these edges are then flattened down against the inner side of the ring by another die or punch from the inside, making a finish somewhat like an eyelet, and firmly, quickly, and economically securing the ring to 45 the jacket. The top edge of the cylindrical jacket is notched in two places, as seen at *g g*, and is wired in the usual way. The wire, however, at points corresponding to the notches 50 *g g*, is bent upward to form ears *e e*, in which is inserted the bail B.

The jacket may, for convenience, be also supplied with a handle, *h*.

Having thus fully described my invention, what I claim as new, and desire to secure by 55 Letters Patent, is—

The herein-described method of securing the jacket to the ring, the same consisting of placing the parts together and driving a hole through both simultaneously, then clinching 60 or flattening the collars thus formed; substantially as and for the purpose set forth.

In testimony that I claim the foregoing as my own I affix my signature in presence of two witnesses.

CHRISTOPH RIESSNER.
